L. WALKER.

BOOT AND SHOE STRETCHER.
APPLICATION FILED JULY 29, 1920.

1,394,871.

Patented Oct. 25, 1921.

UNITED STATES PATENT OFFICE.

LEWIS WALKER, OF RICHMOND, VIRGINIA.

BOOT AND SHOE STRETCHER.

1,394,871.

Specification of Letters Patent. Patented Oct. 25, 1921.

Application filed July 29, 1920. Serial No. 399,755.

To all whom it may concern:

Be it known that I, LEWIS WALKER, a citizen of the United States, residing at Richmond, in the county of Henrico and State of Virginia, have invented certain new and useful Improvements in Boot and Shoe Stretchers; and I do hereby declare the following to be a full, clear, and exact description of the invention, such as will enable others skilled in the art to which it appertains to make and use the same.

This invention relates to two-way boot and shoe stretchers, and consists of certain new and useful improvements in the same, especially directed to simplicity, durability and cheapness of construction.

One of the objects of my invention is to make it possible for a user of my improved device, to stretch a boot or shoe laterally and longitudinally at the same time.

A further object which I have in view, is to provide a stretcher which will have the entire operating mechanism within itself, thereby affording a more compact apparatus and one without any projecting parts which would come in contact with the boot or shoe.

With the foregoing objects outlined and with other objects in view which will appear as the description proceeds, the invention consists in the novel features hereinafter described in detail, illustrated in the accompanying drawing and more particularly pointed out in the appended claims.

Referring to the drawing:—

Figure 1 is a side view of the stretcher showing in dotted lines, interior recesses for receiving the operating mechanism of the device.

Fig. 2 is a plan view showing the two parts of a foot form which is an element of my improved stretcher.

Fig. 3 is a detail view of the interior operating mechanism.

Fig. 4 is a side view of one of the parts of the foot form, showing the interior recesses.

In the drawing 1 designates a foot form, adapted to be placed within a boot or shoe to be stretched, which consists essentially of two like parts, in each of which are two longitudinally extending recesses 1' and 1''. In the rear wall of the recess 1' is an opening 2, which registers with a similar opening 2' in the rear wall of the recess 1''. These two parts are normally held together by means of the rearwardly extending arms 3' of a substantially U-shaped member 3, which

pass through openings in rear walls of the recesses 1'' and upon the outer ends of which there is secured, preferably by frictional contact, a heel part 4.

60

The U-shaped member 3 is pivotally mounted in a lug 5, adapted to operate in the recess 1'', which lug is provided with interior screw threads, adapted to engage the screw threaded part of a longitudinally extending rod 6.

65

The rod 6 is mounted in the openings 2 and 2' provided in the rear walls of the recesses 1' and 1'' and is provided at its outer end with a handle 6', while upon its other end, there is pivotally mounted a substantially arrow-shaped wedge member 7, which operating in the recess 1', is for the purpose of spreading the two parts of the foot form laterally, when the rod 6 is rotated, in its 75 bearings and in the lug 5.

The arrow-shaped wedge member 7 is provided with rearwardly extending hook portions 7' which, when the rod 6 is turned so as to retract the said wedge member, are forced 80 into engagement with the undercut walls of the recesses 1', bring the two parts of the foot form together and lock them in that position.

From the foregoing, the assembling and 85 operation of my improved stretcher is apparent. The two parts of the foot form are brought together and the wedge member and lug are placed in their appropriate recesses, the arms of the U-shaped member extending 90 through the openings provided for them, and the rod being mounted in its bearings and extending rearwardly.

The heel part is then placed upon the ends of the arms of the U-shaped member and the 95 device is ready for use.

When the stretcher is placed within a boot or shoe, it is obvious that upon turning the handle of the rod 6 in one direction, the lug 5 will be retracted, forcing the arms of the 100 U-shaped member and the heel part mounted thereon, backward, until it contacts with the heel portion of the shoe or boot upper, at which time a further turning of the rod 6, will force the wedge member forward and 105 spread the two parts of the foot form, thereby stretching the boot or shoe both laterally and longitudinally.

By rotating the rod 6, in the opposite direction, the heel part may be forced forward, 110 and the hook portions of the wedge member retracted, which, working in the undercut

recesses 1', will draw the two parts of the foot form together and lock them.

It is obvious that my invention may be applied to a right or left last, or to a straight last, also that any suitable material, such as wood, aluminium or other metal, may be used in constructing the different parts.

What I claim and desire to secure by Letters Patent is:-

10 1. A boot and shoe stretcher, comprising a foot form composed of two side parts and a heel part, each of said side parts having two longitudinally extending recesses, one forward of the other, the rear wall of the 15 forward recess being provided with an opening which registers with a similar opening extending through the rear wall of the other recess, a wedge substantially arrow-shaped, adapted to engage the forward recess, a 20 screw threaded lug mounted in the other recess, a longitudinally extending rod, screw threaded at a portion of its length, mounted in the openings in the rear walls of said recesses, said rod engaging the screw threaded 25 lug and being swiveled to the wedge, and means for manually rotating said rod.

2. A boot and shoe stretcher comprising a foot form composed of two side parts and a heel part, each of said side parts having 30 interior recesses, a wedge shaped member mounted in one of said recesses, provided with rearwardly extending hook portions to engage undercut portions of said recesses, an interiorly screw threaded lug member 35 mounted in the other of said recesses, a U-shaped member pivotally mounted in said lug, the arms of which extend rearwardly through the rear walls of the two side parts,

a heel part mounted on the ends of the arms of the U-shaped member, and a longitudinally extending screw threaded rod operatively engaging the lug and being swiveled to the wedge shaped member, whereby when the rod is rotated in one direction, the parts of the foot form will be secured together 45 and when rotated in the opposite direction, the foot form will be extended laterally and longitudinally.

3. In a boot and shoe stretcher, the combination with a foot form made in two parts, each of said parts being provided with interior recesses, of a wedge and screw threaded lug, adapted to engage and operate in the respective recesses, a U-shaped member pivotally mounted in said lug, and having its 55 respective arms pass through the rear wall of one of the side parts of the foot form, a heel part removably mounted on the ends of the said arms, and a rod, operatively engaging the wedge and lug, for spreading the foot 60 form laterally and extending it longitudinally.

4. In a two-way boot and shoe stretcher, the combination with a foot form made in two parts recessed at portions of their length, 65 and being provided with a heel part, of a rod, screw threaded at a portion of its length, a wedge member and an interiorly screw threaded lug member, mounted on said rod, and a member mounted in said lug, provided 70 with means for extending the heel member rearwardly, the said wedge and lug being adapted to lie and operate within the recesses of the foot form.

In testimony whereof I affix my signature. 75
LEWIS WALKER.
